UNITED STATES PATENT OFFICE.

JOHN F. KYTLICA, OF CHICAGO, ILLINOIS.

INTERNAL-COMBUSTION ENGINE.

1,134,623.

Specification of Letters Patent. Patented Apr. 6, 1915.

Application filed March 27, 1914. Serial No. 827,585.

To all whom it may concern:

Be it known that I, JOHN F. KYTLICA, a citizen of the United States, residing at the city of Chicago, in the county of Cook and State of Illinois, have invented certain new and useful Improvements in Internal-Combustion Engines, of which the following is a specification.

My invention relates to internal combustion engines, in which a plurality of oscillating pistons moving in opposite directions are used to drive the crank shaft of the engine.

Some of the more salient objects of my invention are to provide an engine of the above type in which the charge may be compressed before exploding the same, in which the power may be transmitted simultaneously to the same shaft by pistons rotating in opposite directions, and in which the mechanism for operating the intake and exhaust valves and the spark timing means, will be extremely simple and compact.

Other objects and their resultant advantages will become apparent as the nature of my invention becomes better understood from the following description and accompanying drawings, in which—

Figure 1 is a longitudinal section of the engine of my invention complete; Fig. 2 is a vertical section taken through Fig. 1 centrally of the cylinder; Fig. 3 is an enlarged view of the spark timing mechanism; Fig. 4 is an end view showing the intake side of the cylinder portion of the engine; Fig. 5 is an enlarged section through the intake chambers on the cylinder and the casing which houses the valve actuating mechanism; and Fig. 6 is a diagrammatic view of the piston of the engine.

In carrying out my invention, I provide a base frame 1, supporting standards 2 having journals 3 for the ends of a rock-shaft 4, which shaft 4 extends axially through the cylinder 5 of the engine. Rigidly secured to or formed integral with the shaft 4 and extending radially thereof are a pair of diametrically opposed pistons 6, each consisting of a pair of parallel webs between which is arranged a compression spring member 7 and a pair of inter-engaging packing pieces or cams 8, the outer faces of which bear against the inner face of the cylinder 5. Interposed between the shaft 4 and the cylinder 5 on opposite sides of the said pistons 6 are a pair of segmental pistons 9,

which latter are movable relatively to the shaft 4 and the radially disposed pistons 6. Each segmental piston 9 has its opposite faces so disposed that at one extreme of its travel one of these faces will be close to, and substantially parallel to the adjacent face of one of the radial pistons; while at the other extreme of its relative movement, the other face of the segmental piston will be close to, and substantially parallel to the other radial piston. Also each of the said face portions of the segmental piston has a double wall housing two pairs of inter-engaging packing pieces or cams and a spring member tending to separate the said pairs of cams, the outer one of each pair bearing respectively against the shaft and the interior of the cylinder 5.

Both segmental pistons 9 are connected by bolts 10 to a casing or ring 11 spaced from the cylinder 5 by spacing blocks 12. This casing or ring 11 has stiffening webs 13 and formed with an arm or extension 14. The standards 2 also support a main shaft 15 having a central crank 16 and a pair of cranks 17 diametrically opposite to the said central crank. The cranks 16 and 17 are connected respectively by pitmen 18 and 19 to the arm 14 of the casing 13 and to a pair of arms 20 secured to the rock-shaft 4. Consequently, if the pistons 6 and 9 are moved in opposite directions by the explosion of a gaseous mixture between adjacent faces of the said pistons, the motion will be simultaneously transmitted to the crank shaft 15 by the pitmen 19 in one direction and by the pitman 18 in the opposite direction, thereby rotating the shaft. Suitable slots 21 are formed in the cylinder 5 along the line of travel of the spacing blocks 12 to permit the oscillatory movement of the segmental pistons 9 and casing 11 with respect to the cylinder. The cylinder may be rigidly mounted to the frame work of the engine in any suitable manner, as by means of a bracket 22.

Each end of the cylinder 5 is provided with a head plate 23, and a suitable packing ring 24 may be interposed between the head plates 23 and the ends of the pistons 6 and 9. One of the head plates 23, as shown in Figs. 4 and 5, carries four intake chambers 25, each being fitted with a spark plug 26 and each formed with a port 27 leading into the cylinder, the said ports being so disposed as to admit the supply of gas between

adjacent faces of the radial and segmental pistons respectively. The inlet opening to each of the chambers 25 is controlled by a valve 28 which is normally kept closed by a spring 29 and which has a stem 30 projecting radially into a casing 31 formed on the head plate and concentric with the rock-shaft 4. Mounted within the said casing 31 are four pivoted levers 32, each contacting 10 near its free end with the stem 30 of one of the valves 28 and each carrying a roller 33. Loosely mounted on the rock-shaft 4 is a rotatable sleeve 34 provided with a projecting roller 35 which roller will successively engage the respective rollers 33 when the sleeve 34 is rotated about the shaft 4, thereby by successively moving the respective stems 30 against the pressure of the springs 29 and opening the valves 28.

15 To effect the rotation of the sleeve 34 and its roller 35 I fix the sleeve to a gear 36 loosely mounted on the shaft 4 and which is driven in the proper direction through a train of gears 37, the last of which being 20 fixed to a shaft 38 rotatably mounted in suitable bearings to the frame work of the engine, and which in turn is rotated by the crank shaft 15 through gear wheels 39 and 40. The gear 36 also carries a metal disk 41 to which is pivoted a contact arm 42, said disk 41 rotating with the said gear. Arranged adjacent the metal disk 41 is an insulated and stationary ring 43 provided with a plurality of contact plates 44 and binding 25 posts 45 which are connected respectively to the spark plugs 26. The arm 42 is continuously pressed in one direction by a spring 46, thereby insuring a good contact between the roller 47 carried by said arm and the 30 contact plates 44, successively as the disk is rotated.

The head plate 23 for the opposite end of the cylinder is equipped with four exhaust chambers 48, each having ports 49 leading 45 from the cylinder 5 and controlled by valves 50 actuated in precisely the same manner as the valves 28 of the intake chambers 25 through a train of gears 51 from the shaft 38.

To cool the engine, I preferably provide a 50 water cooling system of the siphon type, including chambers 52 connected to jackets 53 partially surrounding the cylinder 5.

It will be evident from Figs. 1 and 6 that the two pairs of relatively movable pistons 55 afford four distinct compartments within the cylinder, in which the cyclic action of the engine takes place successively and which compartments have been designated respectively in Fig. 6 as A, B, C and D. To 60 trace this action it will be assumed that "A" contains a mixture of air and gas under pressure, that B is filled with the spent gases left from a previous explosion, that D has just been filled with air and gas, and that C 65 has just been exhausted of products of com-

bustion. The successive actions of the pistons will then be as follows: 1st: Mixture in A and D—fire A, compress D, exhaust B, fill C. 2nd: Mixture in D and C—fire D, compress C, exhaust A, fill B. 3rd: Mixture in C and B—fire C, compress B, exhaust D, fill A. 4th: Mixture in B and A—fire B, compress A, exhaust C, fill D. After which the same cycle of operations repeats itself. It will be evident from the cyclic action as 70 above traced that by using segmental pistons oscillating between radial pistons, an explosion of gas at one end of the segmental piston will cause the other end of this piston to forcibly approach one of the radial 80 pistons, thereby compressing the charge stored between the approaching pistons, or expelling such spent gas as may be between the same. Also, the connections between the opposed pairs of pistons will cause 85 the exploding of the charge in any one of the said four chambers to effect an expansion of the chamber diametrically opposed to the chamber in which the charge was exploded, thereby enabling the said expanding chamber to suck a fresh charge into its interior. Thus, the successive exploding of the charges in the consecutive chambers will enable the other chambers successively and in rotation to empty themselves, fill themselves and 90 compress their contents ready for effective ignition.

To effect the desired timing of the spark or firing with respect to the positions of the pistons and the operating of the valves, the 100 metal disk 41 may be moved with respect to the insulated ring 43, thereby causing the ignition to occur either earlier or later as desired.

To provide ample oiling for the crank shaft, the pitmen and their connections, the same may be inclosed in a casing 54 from which the oil may be drained when necessary by a cock 55, also to improve the steadiness of the engine and to supply momentum 110 to the crank shaft and its pitmen, said crank shaft is provided with a fly wheel 56, which in turn may carry a clutch 57.

While I have shown and described my invention in its preferred form, it will be evident that the various details of construction disclosed may be changed in many ways without departing from the spirit of my invention, and I therefore do not wish to be limited to the exact structure shown.

I claim:

1. In an internal combustion engine, the combination with a stationary cylinder, of a rock-shaft extending therethrough, a pair of pistons rigidly connected to the said shaft and disposed radially of the cylinder; a pair of segmental members movably interposed between the said shaft and the walls of the cylinder; a crank-shaft carrying oppositely disposed cranks, a ring extending 125

around said cylinder and rigidly connected to the segmental members, and pitmen connecting the oppositely disposed cranks respectively to the said rockshaft and the said 5 ring.

2. In an internal combustion engine, the combination with a stationary cylinder, of a rock-shaft extending therethrough, a pair of pistons rigid with respect to the said 10 shaft and disposed radially of the cylinder; a pair of segmental members movably interposed between the said shaft and the walls of the cylinder, each of the said members presenting walls disposed close to and substantially 15 parallel with one of the other of the pistons between which the said member is interposed, according as the said member and pistons are at one or the other extreme of their relative motion; a crank-shaft carrying oppositely disposed cranks, an annular ring extending around the said cylinder and rigidly connected to the segmental members, spacing blocks interposed between said 20 ring and the segmental members and working in slots formed in said cylinder, and pitmen connecting the oppositely disposed cranks respectively to the said rock-shaft and the said ring.

3. In an internal combustion engine hav-

ing a plurality of substantially radially disposed and relatively movable pistons housed between a cylinder and the shaft extending axially through the latter, and having ports for connecting intake and exhaust pipes to portions of the cylinder disposed between 30 adjacent faces of the said relatively movable pistons, means for controlling the said ports comprising a normally closed valve controlling each port, the said valves disposed outwardly of a cylinder casing concentric with the said shaft, each of the said valves having a stem projecting radially into the said casing; a plurality of actuating levers mounted within the said casing and contacting respectively with the said stems 35 of the valves; a rotating member loosely mounted upon the said shaft and adapted when rotated to successively engage the said actuating members to cause the latter successively to operate the said valves; and, 40 connections between the main shaft and the engine and the said rotating member for 45 effecting rotation of the latter.

JOHN F. KYTLICA.
